BUILDING CONSTRUCTION

Robert B. Muse, San Francisco, Calif., assignor
to Barrett & Hilp, San Francisco, Calif., a co-
partnership consisting of J. Frank Barrett and
Harry H. Hilp

Application March 8, 1938, Serial No. 194,573

5 Claims. (Cl. 72—1)

This invention relates generally to the construction of houses and other buildings, and particularly to the construction and erection of exterior and interior walls.

In the past the use of re-enforced concrete in the construction of housings and other buildings, has been limited to pre-cast concrete blocks, or re-enforced steel walls which are poured as the walls are erected. For low cost housing, concrete blocks are not suitable, because of the time and expense involved in laying the blocks with mortar. Furthermore a concrete block construction does not afford the strength which is ordinarily associated with re-enforced concrete. Reinforced concrete walls poured as the building is being erected afford maximum strength, but are likewise unsuited to low cost housing, because of the time and labor required for erection, and because of the amount of concrete employed for a given area of wall. The use of pre-cast concrete panels has been proposed, as a substitute for smaller blocks, but insofar as I am aware, these panels are relatively expensive because of the steel framing required, and they involve considerable time and expense for erection, due to the necessity of making connections between the panels and with load bearing pilasters.

It is an object of the present invention to provide a building construction which will gain all of the advantages of re-enforced concrete, but at a minimum of cost for pre-fabrication and erection. In carrying out the present invention I make use of pre-cast re-enforced concrete wall sections, which are devoid of expensive steel framing, and which are directly coupled together to form the various walls and wall intersections. The wall sections are relatively large in size, and for houses of one or two stories, they extend the full wall height.

A further object of the invention is to provide a novel type of joint for the wall sections, whereby upon erection of the wall sections it is possible to align them accurately, before the joint is made permanent and rigid.

Another object of the invention is to facilitate and make possible the accurate erection and alignment of pre-cast concrete wall sections, whereby pre-cast floor panels can be applied and attached to the wall sections.

Further objects of the invention will appear from the following description in which the preferred embodiment of the invention has been set forth in detail in conjunction with the accompanying drawings.

55 Referring to the drawings:

Fig. 1 is a schematic lay-out, showing a house plan suitable for use with my construction, and involving varied junctions between the wall sections.

Fig. 2 is a perspective view, illustrating a pair of wall sections constructed and erected in accordance with the present invention, together with pre-cast concrete floor and roof slabs.

Fig. 3 is a cross-sectional view taken along the line 3—3 of Fig. 2.

Fig. 4 is a cross-sectional detail, showing the construction of the corner joint numbered 4 in the house plan of Fig. 1.

Fig. 5 is an enlarged cross-sectional detail, illustrating the construction of the T-joint marked number 5 in the house plan of Fig. 1.

Fig. 6 is an enlarged cross-sectional detail, illustrating the joint marked number 6 in the house plan of Fig. 1, and involving a straight connection between aligned wall sections.

Fig. 7 shows a T-intersection between wall sections, and corresponds with the joint 7 of Fig. 1.

Fig. 8 is an enlarged cross-sectional detail, showing a cross-intersection corresponding to the joint numbered 8 of Fig. 1.

Fig. 9 is an enlarged cross-sectional detail, showing a T-intersection between wall sections, and corresponding to the joint numbered 9 of Fig. 1.

Fig. 10 is an enlarged cross-sectional detail, illustrating the manner in which floor slabs are attached to the wall sections.

Fig. 11 is an enlarged cross-sectional detail showing the manner in which the lower edges of the wall sections can be anchored to a foundation.

Fig. 12 is an enlarged cross-sectional detail showing the manner in which a window casing is formed in a wall section.

Fig. 13 is an enlarged cross-sectional detail showing a floor joint construction.

Fig. 14 is a side elevational view in cross-section, showing a modified form of wall section on a modified type of joint between wall sections and floor slabs.

Fig. 15 is a side elevational view of the uppermost joint of Fig. 14, looking toward the inside surface of the wall sections, with the wall board surfacing removed and with the floor slab in cross-section.

Fig. 16 is a cross-sectional detail, showing a modified form of floor construction.

As illustrated in Figs. 1, 2 and 3, my construction makes use of re-enforced concrete wall sections 10, which are pre-fabricated or pre-cast at

55

some suitable plant or factory, and erected in the manner to be presently described. The height of these wall sections depends upon the design of the building being constructed. For low cost 5 home construction, the sections extend for the full height of the building. Thus where the building is of only one story in height, the wall sections are of a height extending from the foundation upon which they are erected, to a point 10 above the roof deck. Where walls of a two-story height are required, the wall sections extend the full two stories, to a point above the roof deck.

The wall sections for a building are not 15 exact duplicates, except in certain instances where two or more duplicate sections may be employed. However, the majority of all the wall sections making up a complete building have certain features in common. Thus each of the two wall 20 sections illustrated in Fig. 2 are formed with integral ribs 11 on the inner side of the wall, and extending in a vertical direction. At the lower end of each wall section there is a flange or rib 12, for engaging with the foundation 13. Near 25 the upper edge of each wall section there is a flange or rib 14 which connects together the upper ends of ribs 11, and which forms a ledge for supporting the roof deck 16. For wall sections which extend two stories in height, there is also 30 a horizontal rib 17, which forms a ledge for supporting the second floor 18. The lower floor 19 is carried by the foundation 13, as will be presently explained. The vertical edges of the wall sections also have inner flanges or ribs, which are 35 variously proportioned, according to the type of joint with which it is to be used.

Wall sections such as described can be formed by the use of suitable molding equipment, involving the use of high frequency vibrators. 40 Metal re-enforcement can be provided as is well known to those skilled in the art, in order to afford the desired degree of strength required.

Reference is made, by way of example, to the typical floor plan of a house, shown in Fig. 1. 45 This floor plan involves the use of the exterior wall sections *a*, *b*, *c*, *d*, *e*, *f*, *g*, *h*, *i*, *j*, and *k*, and the major interior partitions *p*, *m*, *n*, and *o*. It also involves the use of certain joint intersections, including particularly the intersections 50 numbered 4 to 9 inclusive.

Each of the various joint intersections provided, between the wall sections, are such that the walls can be initially connected together as they are erected, whereby after such a connection is established, the connections can be shifted to exact alignment. Thus the simple right angle joint intersection numbered 4, illustrated in Figs. 3 and 4, makes use of the wall sections 55 *10a* and *10k*. The adjacent edges of these wall sections are provided with recesses 21 and 22 which are substantially in registry, and which form a common space extending within the joint the full height of the wall. The members serving to form an articulated connection between the two wall sections, include the U-shaped or bail-like bars 23, together with bars 24 carried by the wall section *10k*. Bars 23 are disposed at spaced intervals along the height of the section *10a*, as shown in Fig. 3, and are embedded 60 in the concrete. Bars 24 are loosely disposed within the holes 26 formed in section *10k* and are retained by nuts 25. They have free end portions 27 which are bent downwardly, to engage within the bails 23. Before erecting the 70 wall sections *10a* and *10k*, the bars 24 are loosely 75

attached to the section *10k*. When the two wall sections are hoisted into place upon the foundation, the downwardly bent portions 27 can be aligned generally above the bails 23, to hook within these bails as wall section *10k* is lowered into place. Thereafter both wall sections can be shifted with respect to each other, and with respect to other walls and parts of the building, to secure accurate alignment.

The adjacent end faces 29 and 30 are spaced 10 apart, and such spacing is retained after the sections have been properly aligned. Thereafter, to complete the joint, wedges 31 and 32, or some other suitable form of obstructions, are applied to close the inner and outer faces of the 15 joint, after which the space provided by the recesses 21 and 22 is filled with cement mortar or grouting. After this cement has hardened a rigid point is formed, which is re-enforced by the steel bars 23 and 24. Thereafter wedges 31 and 20 32 can be removed, and any suitable type of surfacing or troweling applied to enhance the appearance of the joint.

Fig. 5 corresponding to joint numbered 5 of Fig. 1, is in some respects similar to Fig. 4, but 25 involves the intersection of an interior partition with two outer wall sections. In this instance the two adjacent edges of the aligned wall sections *10a* and *10b*, have recesses 33, which together with the recess 35 of wall section *10p*, form 30 a space extending the entire wall height, within the joint. The outer wall sections are loosely connected together by the bars 34, which extend through openings 36 in the concrete of the sections, and which have their ends threaded to receive the nuts 37. Bars 34 are engaged by the bars 38, which loosely fit within the openings 39 of wall sections *10p*. Bars 38 are threaded to receive the retaining nuts 41, and their inner ends 42 are bent downwardly to engage behind the 40 bars 34.

In forming a joint of the type illustrated in Fig. 5, wall sections *10a* are first hoisted into place and connected together by means of the bars 34. Thereafter the inner partition *10p* is erected 45 with the bars 38 attached to the same, and as wall section *10p* is placed in generally final position, the ends 42 of bars 38 are engaged and interlocked with bars 34. Now, as with the joint of Fig. 4, the three wall sections can be 50 shifted to secure proper alignment with respect to each other, and with respect to other parts of the building. Thereafter the space formed by the recesses 33 and 35 is filled with cement mortar or grouting, in the same manner as the joint 55 of Fig. 4.

Fig. 6 illustrates a simple joint between two wall sections disposed on a common wall center. In this case the two wall sections *10b* and *10c* are connected together by means of the steel 60 bars 44, corresponding to the bars 34 of Fig. 5. These bars are fitted loosely within the openings 45, and are threaded to receive the retention nuts 47. Bolts 44 are placed in position and the nuts 47 applied, after the two wall sections have 65 been hoisted into position upon the foundation. Thereafter, as with Figs. 4 and 5, the two wall sections are shifted to proper aligned position, after which the spaces in the joint, formed by the aligned recesses 46, are filled with cement 70 mortar. Fig. 6 also serves to illustrate a type of joint which can be used to insure against leakage. Thus in this instance, before filling in recesses 46, a strip 48 of compressed expandible cork is inserted between the end faces 49. There- 75

after the recesses 46 are filled in the same manner as Figs. 4 and 5. The exposed edge of the cork strip 48 can be covered by any suitable form of protective coating, such as paint, or a layer of cement mortar. Compressed cork, by absorption of moisture, expands and forms a permanent liquid-tight seal between the faces 49, irrespective of expansion and contraction which may occur.

10 Fig. 7 illustrates a T-intersection where one partition or exterior wall intersects an intermediate part of an outer wall section. Thus in this instance an intermediate part of wall section 10e, is provided with a recess 51, in substantial registry with the recess 52 formed on the adjacent end face of wall section 10f. Also the wall section 10e is provided with the bars 23, corresponding to the bars 23 of Fig. 4. Wall section 10f is provided with bars 24, corresponding to those of like number in Fig. 4, and these bars are likewise provided with the down-turned end portions 28, to engage and interlock with the bars 23. The filling of this joint with cement mortar is the same as with the other joints described. It can also be provided with the cork sealing strip 48, the same as Fig. 6.

Fig. 8 illustrates a wall intersection, where the end edges of four walls terminate at a joint. In this instance interior partitions are involved, although a similar type of joint might be used for exterior walls. Thus the panel sections 10p and 10o are loosely connected by the lateral steel bars 54, which have their ends threaded to receive the retention nuts 56. Wall sections 10m and 10n are also loosely connected by the bars 57, which have their ends threaded to receive the retention nuts 58. As viewed in plan the bars 54 and 57 intersect at right angles. The end faces of wall sections 10m and 10n are spaced apart sufficiently far to amply clear the bars 54, while the adjacent end edges of panel sections 10p and 10o are spaced apart a distance somewhat greater than the thickness of wall sections 10m and 10n. Sections 10m and 10n have recesses 59 while the adjacent edges of sections 10p and 10o have recesses 61, which are in communication with the former recesses through the spacing 62, between sections 10m and 10n. All of the communicating spaces within the joint are then filled with cement mortar in the manner previously described, to form a rigid joint. Here again the joint as finally formed has the cement mortar re-enforced by the steel bars 54 and 57.

Fig. 9 illustrates a T-intersection, where the line of centers of the right-angle wall section is offset with respect to the center of the joint between the other two sections. Thus in this instance the wall section 10k is formed similar to the wall section 10a of Fig. 4, except that its end edge is formed with a recess 63. The adjacent edge of wall section 10j is likewise provided with a registering recess 64, and initially the two sections 10k and 10j are loosely connected by the bars 66. Wall section 10k is provided with bars 23, the same as in Fig. 4, and which cooperate with the bars 24 formed in the section 10m. The joint between sections 10k and 10m can be finished the same as with Fig. 5, while that between sections 10k and 10j is substantially the same as in Fig. 6.

With all of the wall sections it is desirable to employ means to facilitate application of an internal wall surfacing. Thus with the various wall sections, used in making the joint intersections described with respect to Figs. 4 to 9 includ-

sive, the sections are shown provided with inset wooden strips 68. To these strips suitable wall boarding 69 can be applied, or if desired other forms of wall surfacing can be attached, as for example lath and plaster, or expanded metal to which the plaster can be applied. Corners, made by the interior wall boards, can be finished in any desired manner, as by the use of moulding strips cemented in place.

It is possible to use conventional types of floor and roof constructions, that is, constructions making use of wood beams and conventional floor boarding. However, in keeping with the fire proof nature of the wall sections, I prefer to make use of floor slabs or panels, formed of pre-cast re-enforced concrete. For example, in Figs. 2, 3 and 10, the roof deck 16 is formed of the two precast concrete slabs 16a and 16b. These slabs are provided with ribs or beams 72, on their lower sides, and their edges rest upon 20 and are supported by the ribs 14 of the wall sections. To form a permanent connection between such slabs and the wall sections, an arrangement as shown in Fig. 10 can be employed. Thus in this instance the edges of the slabs are 25 provided with preformed openings 73, and when the wall sections are properly aligned, these openings register with openings 74, formed in the flanges 14 of the wall sections. Suitable reinforcements can be provided in connection with 30 these openings, such as the U-shaped rods or bars 75. After the slabs have been properly located, with hole 73 in registry with holes 74, cement grouting can be poured into these openings, and then steel dowels 76 inserted, to form 35 a permanent rigid connection. With respect to alignment of the wall sections to properly connect with the floor and ceiling slabs, it may be pointed out that during erection of the wall sections, suitable templates can be applied whereby 40 the openings 74 are properly located, to accurately register with the pre-formed slabs.

The number of slabs used in forming the floor or ceiling deck, will depend upon the size of the slabs, and the area of the floor or deck. Generally it is desirable for the slabs to extend completely across the floor or ceiling area, with the longitudinal edges of adjacent slabs slightly overlapping. Thus, in Fig. 2 the edge 77 of slab 16b, rests within the recess 78, formed in the slab 16a. 50

The slabs forming the intermediate floor 18 can be substantially the same as the roof deck 16. However, in this instance the sides of the slabs which engage the ledges 17, are shown provided with extensions 81, which are attached by 55 dowels or pins to the ledges 17, in the same manner as described in Fig. 10. The lower floor slabs 19a and 19b can be substantially the same as the slabs forming the roof deck. The edges of this floor deck are shown directly supported by the 60 foundation 13.

Fig. 13 illustrates a desirable form of joint between the longitudinal edges of adjacent floor slabs. In this instance, as the slabs are assembled, cement grouting is applied to the supporting shoulder 82, and also between the adjacent edges of the slabs, as indicated at 83. The upper faces of the two slabs are also recessed as indicated at 84, and after the slabs are assembled a suitable filler 86 is applied in recess 84, to afford a smooth continuous floor surface. The filling 86 can be conveniently a strip of linoleum or like composition, applied and retained in place by means of a suitable cement or adhesive.

Fig. 11 illustrates a convenient type of connec-

75

tion between the foundation and the wall sections. Thus the lower edges of the wall sections 10 rest upon the top 87 of the foundation 13. Mortar or grouting 88 is applied to seal the 5 joint and to secure a good bearing area for the wall. The lower flanges 12 of the wall sections, have openings 89, and these openings serve to receive the anchoring bolts 90. The adjacent edges of the floor slabs 19 also rest upon the 10 foundation 13, as illustrated. These wall sections are to be provided with doors or windows, the door framing, or window frames, and are embedded in the proper sections at the time these 15 sections are molded. As an example of this practice reference is made to Fig. 12. Here a window opening 92 in one of the wall sections 10, is provided with a steel window frame 93, which is embedded in the concrete of the wall sections. Thus 20 after erection of such wall sections it is only necessary to apply the moving sash.

The outer surfaces of the walls can be treated in any desired manner, as for example by painting, stucco, or a waterproof Portland cement wash. In general no particular exterior 25 surface treatment is necessary, since the wall sections will possess smooth even textured surfaces. The inner surfaces of the wall sections can be treated with inexpensive coating materials, such as asphaltic emulsion. The floor surfaces can 30 be stained, painted or otherwise treated as desired. For bath and kitchen floors, or elsewhere if desired, the floor slabs can be given a monolithic "Terrazzo" finish 85 (Fig. 13). Preferably the Terrazzo mix is applied to the floor slabs 35 as a skim coat, after the concrete of the slab has initially set, but before setting is complete. After the slabs have been cured the surface is ground and polished.

Figs. 14 and 15 show a modification in which 40 the wall sections extend for only one story in height with the ends of the wall sections engaging floor slabs. Thus in this instance the lower floor slabs 96 rests upon the foundation 97, and the wall sections 98 for the first story of the 45 building, rest upon the slabs 96. The floor slabs 99 for the second story in turn have their edges interposed between the upper ends of the lower wall sections 96 and the upper wall sections 101. The junctions between the end edges of the wall 50 sections, and the floor slabs can include the anchoring rods 102, extending from the foundation, and the tie bolts 103 for the upper floor decks. Also these junctions are filled with grouting and 55 are preferably provided with recesses, to be filled with grouting, in order to provide an interlock. Thus each junction between a wall section and a floor slab is shown provided with the registering recesses 104 and 105. When a joint is initially 60 established a suitable reenforcement 106 can be placed in the spaces provided by recesses 104 and 105, and steel wedges or like means are used to keep the opposed faces separated a slight amount. After securing proper alignment the spaces formed by recesses 104 and 105 are filled 65 with grouting 107, which can be introduced through openings 108 or 109. Such joints can also be provided with strips 111 of compressed cork, in order to prevent leakage.

Fig. 16 shows a modified form of floor construction in which separate joists 112 serve to support 70 a flat floor slab 113. Such separate joists can be used with the arrangement of Fig. 10, or their ends may be disposed in recesses 114 and 115, formed in the adjacent edges of wall sections 75 116 and 117.

It will be evident from the above that my invention makes it possible to construct houses and other buildings at a minimum of cost, but of first-class fire proof materials having a high degree of strength. Houses constructed in accordance with my plans require a minimum amount of expense for maintenance, and are subject to a minimum amount of deterioration. Erection of the main portions of the house, including the walls, inner partitions, and floors and ceiling, 10 can be carried out in a minimum amount of time. The concrete wall sections and also the floor and ceiling slabs can be pre-formed to a high degree of accuracy, and as previously explained, the manner in which the walls 10 are 15 connected together and erected, makes it possible to have all of the walls in exact alignment, for receiving, and interlocking with the floor and ceiling slabs. My invention is particularly applicable to large scale erection of houses, where 20 a large number of houses are substantial duplicates, and where they are to be erected in accordance with a community plan.

I claim:

1. In a building construction, a pair of upright 25 wall sections formed of pre-cast concrete, said sections being of a height at least equal to one story of the building, adjacent edges of said sections, at a wall junction, being provided with recesses which are in substantial registry to form 30 a space extending substantially the entire height of the wall sections, metal members serving to form a loose connection between said wall sections during erection and alignment of the same, the adjacent edges of said wall sections on the 35 outer side of the wall having spaced parallel end faces extending for the entire height of the wall sections, a strip of compressed expandable cork disposed between said end faces and serving to seal the joint, and cement mortar within the 40 aforesaid space to afford rigidity for the joint.

2. In a building construction, at least two vertically extending wall sections, said wall sections being of a height at least equal to one story, and metal members forming an articulated connection 45 between the adjacent vertical edges of said wall sections, said members including laterally extending bars attached to the vertical edges of said wall sections and disposed within the inner and outer faces of the sections, said bars being 50 adapted to directly interlock.

3. In a building construction, a pair of vertically extending wall sections of pre-formed concrete, said sections being of a height at least 55 equal to one story of the building, rigid connecting members extending laterally from the adjacent vertical edges of said wall sections, said connecting members being adapted to loosely interlock to form an articular connection between the two wall sections, the interlock being established by vertical movement of one wall section 60 with respect to the other.

4. In a building construction, a pair of vertically extending wall sections, said sections being disposed at right angles to each other whereby 65 adjacent edges form a right-angle corner, recesses formed in the adjacent vertical edges of the wall sections, said recesses being substantially in registry whereby a space is formed in the joint 70 extending for substantially the entire height of the wall sections, a plurality of metal bars secured to said wall sections and having portions disposed in said space, said portions being in the form of bails, and a plurality of metal bars secured to the adjacent edge of the other wall sec- 75

tion, said last named bars being adapted to directly engage within said bails.

5. In a building construction, at least two vertically extending wall sections, said wall sections being of a height at least equal to one story, and means forming a temporary articulated connection between the adjacent vertical edges of said wall sections, said means including rigid bars at-

tached to the vertical edges of said wall sections, said bars having portions extending into the space between said vertical edges, said portions being loosely interlocked, at least one set of said bars for one wall section being loosely extended through openings in the wall section and being threaded to form draw bars. 5

ROBERT B. MUSE.
